UNITED STATES PATENT OFFICE.

THEODORE F. WILSON, OF WASHINGTON, DISTRICT OF COLUMBIA.

CAMP EQUIPMENT.

1,158,356.

Specification of Letters Patent. Patented Oct. 26, 1915.

Application filed February 25, 1915. Serial No. 10,526.

To all whom it may concern:

Be it known that I, THEODORE F. WILSON, a citizen of the United States, residing at Washington, in the District of Columbia, 5 have invented a certain new and useful Camp Equipment, of which the following is a specification.

This invention relates to camp equipment and is especially designed for camp equipment such as is used by soldiers on the 10 march and in camp.

Especially the invention relates to a device capable of being used, in whole or in part, as either a shelter tent, bed, stretcher, 15 hammock and knapsack.

The principal object of the invention is to provide an improved and simplified article adapted to be carried by a soldier or other person in campaigning or camping trips.

20 A second object of the invention is to provide a shelter tent section which can be utilized as a knapsack when desired.

A third object of the invention is to provide a shelter tent section which can be 25 united to a second section to form a hammock or stretcher.

A fourth object of the invention is to provide a shelter tent section which can be combined with other sections to form a bed 30 capable of being stuffed with straw or other suitable material.

With the above and other objects in view the invention consists in general of certain 35 novel details of construction and combinations of parts hereinafter fully described, illustrated in the accompanying drawings and specifically claimed.

In the accompanying drawings, like characters of reference indicate like parts in the 40 several views, and: Figure 1 shows a complete four section tent in perspective. Fig. 2 shows a perspective of the shoulder side of a section of the device when arranged to form a knapsack. Fig. 3 shows a view similar to Fig. 1 but taken from the rear. Fig. 4 shows a plan view of one of the sections. Fig. 5 shows the knapsack frame assembled 45 in perspective. Fig. 6 is a detail perspective of the end of one of the frame members. Fig. 7 is a perspective view of the device arranged for use as a hammock. Fig. 8 is a perspective view of the device in use as a stretcher. Fig. 9 is a perspective view of the device in use as a bed.

50 In the construction of the device shown in the present application the same are made

from one or more units all substantially alike in form and construction which may, or may not be used with certain frame bars and rods as may be necessary to subserve the different 50 purposes desired. These units may, in the larger sizes, each be carried by an individual or two units may be carried by a single person in the smaller sizes of the device, just as one-half a shelter tent is now carried during a campaign by each soldier. In either case each unit comprises, as best seen in Fig. 4, a rectangular body portion 10 having on one side a triangular flap 11, there being between these portions a row of gromets 12. Adjacent the bottom edge of each unit are arranged eyelet ring members 13 for the reception of peg receiving loops 14. Along the edge opposite the flap 10 is a double row of fastening means such as snap 65 button members 15 of the ordinary type. Along the edge opposite the eyelets 13 is a single row of similar members 16. Spaced to form a quadrangle about the center of the body 10 are loops 17 to receive the knapsack 70 straps 18, to the loops being provided with snap members 19 adapted to coöperate with companion members (not shown) on the straps, the latter also having snap members 20 engageable with coöperating members 21 75 on the body 10. Along the edge of the flap 11 is a row of lacing eyelets 22. Coöperating with each of these units is a knock-down frame consisting of two sides 23 and two sides 24, the former being provided at each 80 end with a pair of pegs 25 receivable in openings 26 in the latter which, moreover, are provided with pole receiving openings 27 and hooks 28 spaced as are the gromets 13.

When in use as a knapsack the flap 11 is 85 folded on the body 10 and the frame, it having been assembled as in Fig. 5, is placed on the body over the flap. The body is then folded about the frame to the form shown in Figs. 2 and 3 provision being made for attaching the free ends of straps 18 by loops 28 on said straps and buttons 29 on the body.

Blanket straps 30 are attached to the device by coacting snap members 31 and 32.

In using the device as a tent four units are 105 assembled in the manner shown in Fig. 1, and poles 33 and a ridge pole 34 being employed as shown in the figure. When the device is employed as a hammock two units such as form one side of the tent are used, 110 these being folded along a line half way from bottom to top as in Fig. 7. Then the

frame members 27 are hooked into the gromets 12 and a suitable suspension rope 35 secured in the openings 27, the rope being replaced by poles 36 having abruptly tapered ends 37 when the device is used as a stretcher. To form a bed or mattress a tent side composed of two members is folded along the connecting line of said members and a lacing 38 is run through the gromets, the bag 10 thus formed being stuffed with hay or the like. There has thus been provided a simple and efficient device of the kind described and for the purpose specified.

Having thus described the invention, what is claimed is:

An accoutrement unit comprising a rectangular strip of fabric having a row of attaching devices along one of its longer edges,

and means on the opposite longer edge adapted to engage with coöperating means 20 on a second similar unit, one of the shorter edges of the unit being provided with a row of attaching devices and having means on the opposite shorter edge adapted to engage coöperating means on a third, and a triangular flap having one edge secured to the first mentioned longer edge of the strip and spaced inwardly from the edge beyond the attaching devices.

In testimony whereof, I affix my signature, 30 in the presence of two witnesses.

THEODORE F. WILSON.
